De Bellis,

UNITED STATES PATENT OFFICE.

GENNARO DE BELLIS, OF PHILADELPHIA, PENNSYLVANIA.

MUSICAL CHART.

1,172,442.

Specification of Letters Patent.

Patented Feb. 22, 1916.

Application filed December 11, 1913. Serial No. 805,970.

To all whom it may concern:

Be it known that I, GENNARO DE BELLIS, a subject of the King of Italy, residing at Philadelphia, in the county of Philadelphia, and State of Pennsylvania, have invented 5 certain new and useful Improvements in Musical Charts, of which the following is a specification.

This invention relates to musical charts 10 and more particularly to that form of chart intended to be placed above the key board of a piano to enable the student to readily pick out the key corresponding to a given note.

The objects of my invention are to provide 15 a device of this character of pleasing appearance, and simple construction, which may be easily folded into small space for transportation, and which may be quickly set up on the piano without defacing or injuring the case. 20 I have also arranged my chart in such a way that the same gives an accurate reproduction of a key board, the divisions or keys tallying exactly with the keys of the piano upon which it is placed and the notation thereon 25 being so arranged that the student may readily find the key corresponding to the note on his or her music.

With these and such other objects in view 30 as may hereinafter more fully appear, my invention consists in the novel arrangement and construction of parts described in the following specification, more particularly pointed out in the claims, and which are shown in the accompanying drawings, 35 wherein:—

Figure 1 is a front elevation of the device 40 in position on a piano. Fig. 2 is a plan view of the device, the same being shown partly folded. Fig. 3 is a front elevation showing in broken detail the bass portion of the device. Fig. 4 is a front elevation showing in broken detail the treble portion of the device.

Referring to said drawings by numbers:—The chart is formed of a convenient number of sections 1, formed of card board, celluloid, wood or other suitable material, the sections being flexibly joined in any convenient manner, but preferably by 45 hinges 2. To the end sections are flexibly fastened strips 3, carrying on their lower ends the foot pieces 4, said foot pieces being preferably shod with rubber, felt or other suitable material to prevent scratching or 50 defacement of the piano when the device is placed thereon.

To hold the device securely in an open position, when in use, any suitable means may be employed such as the clip 5 which is adapted to fit firmly over the edge of the device, at the joints thereof, and is provided with a slot 6 for the reception of the hinge 2. When the device is folded into book form the same may be secured by any suitable catch such as the clip 7 formed to fit 65 snugly over the edge of the folded device, as shown most clearly in Fig. 5.

The surface or face of the device so formed, is divided by suitable lines 8 to represent the key board of a piano and across the keys so represented is drawn the musical staff and, where necessary, the leger lines above or below the same, as the case may be. On each key is placed the note struck by 70 said key and also the letter and name of said 75 note.

It will be noted that the letters, used in notation in instrumental music, are placed below the staff in the bass while the syllabic notation is placed above the staff, while in 80 the treble the position is reversed, the letters being placed above the staff and the syllabic equivalents below; thus giving a ready and positive indication of the change of clef.

By reference to Figs. 3 and 4, it will be 85 noted that the staff and leger lines, where necessary, are shown on each key and the note corresponding to said key also placed thereon so that one may readily locate said note on the music which is being played. As 90 a further aid to the student the octaves in the different clefs are marked most plainly on the chart.

It will also be noted that the black keys, which are used to strike either sharps or 95 flats, are provided with double notation to indicate the note of which said key will strike the sharp and also of what note it will strike the flat.

The device is folded into book form, as 100 shown in Fig. 5, when not in use. When to be used the clips 7 are removed and the sections unfolded, the clips 5 are placed in position at the joints the ends 3 bent at right angles to the sections 1 and the device placed 105 upon the piano, above the key board, as shown most clearly in Fig. 1.

Having described my invention, what I claim as new and desire to secure by Letters Patent, is:—

1. A musical chart comprising boards having hinged connection, and adapted to be

- supported in a vertical position above the keys of a piano, said boards having on their front faces lines indicating the facsimile of a piano key board registering with the key board of the piano on which the chart is supported, and a musical staff extending across the outer portion of the white keys, and two separate staves across the black keys, every representation of a key on the chart bearing 5 a note located on the proper degree of the staff, one staff on the black keys bearing the appropriate sharp signs, the other staff bearing the corresponding flat signs, substantially as described.
- 10 2. A musical chart comprising boards having hinged connection, and adapted to be supported in a vertical position above the keys of a piano, said boards having on their front faces lines indicating the facsimile of
- 15 a piano key board registering with the key board of the piano on which the chart is supported, and a musical staff extending across the outer portion of the white keys, and two separate staves across the black keys, every representation of a key on the chart bearing 20 a note located on the proper degree of the staff, one staff on the black keys bearing the appropriate sharp signs, the other staff bearing the corresponding flat signs, all of said staves having a syllabic notation and alphabetical notations, substantially as described.
- 25 In testimony whereof I hereunto affix my signature in presence of two witnesses.
- GENNARO DE BELLIS.

Witnesses:

CHARLES B. ROSA,
SILVIS GIARDINELLI.
